WEB PERFECTING ROTARY PRESS

Howard M. Barber, Pawcatuck, Conn., assignor
to C. B. Cottrell & Sons Company, Westerly,
R. I., a corporation of Delaware

Application April 9, 1937, Serial No. 135,853

6 Claims. (Cl. 101—179)

In high speed web perfecting rotary presses where quick drying inks and web drying units are employed, it is very desirable that the several units be so located with respect to each other 5 as to produce the best results while occupying a minimum amount of space.

The object of my invention is to so locate the printing and drying units and the web supply roll that the web can be fed and printed and 10 the inks dried with a minimum travel of the web.

My invention comprises, generally, lower and upper multicolor printing units, lower and upper drying units, each printing unit consisting of an impression cylinder and a plurality of form cylinders arranged in each printing unit around the side of the impression cylinder opposite a drying unit, and inking mechanisms for the form cylinders, said printing and drying units being all located in line with one another, the printing units in substantially the same transverse vertical plane and the drying units in substantially the same transverse vertical plane, an oil offset mechanism for the second impression cylinder and a web supply roll. Means are provided for passing the web from the supply roll to and through the lower printing unit, then to and through the lower drying unit, then to and through the upper printing unit, then to and through the upper drying unit, and finally directing the web in the desired direction, as, for instance, to a delivery point at the end of the press.

Practical embodiments of my invention are represented in the accompanying drawings, in 35 which

Fig. 1 represents a diagrammatic side elevation of one form of my invention where a single web is perfected in four colors; and

Fig. 2 represents a diagrammatic side elevation of another form of my invention where a single web is perfected in two colors.

In Fig. 1, the lower printing unit is represented as a four color unit, the impression cylinder being denoted by 1 and its four form cylinders by 2, 3, 4, 5, which form cylinders are arranged around the side of the impression cylinder opposite a drying unit. The inking mechanisms for the four form cylinders are denoted by 2a, 3a, 4a, 5a, which inking mechanisms apply the inks to their respective form cylinders in the usual manner.

The upper printing unit for perfecting the web is herein represented as a four color unit, the impression cylinder being denoted by 6 and its

four form cylinders by 7, 8, 9, 10, which form cylinders are arranged around the side of the impression cylinder opposite a drying unit. The inking mechanisms for the four form cylinders are denoted by 7a, 8a, 9a, 10a, which inking mechanisms apply the inks to their respective form cylinders in the usual manner.

These two printing units are located in line with each other at the required distance apart and they are also preferably located in substantially the same transverse vertical plane.

An oil offset mechanism 11 of a well known or approved form may be used for the purpose of keeping the packing clean on the upper impression cylinder 6 and eliminating not only smut that might be caused when the web is not absolutely dry, but will also remove from the packing any dried particles of ink that may be picked off by the make-ready when receiving the impression from the upper printing unit.

The lower drying unit is herein represented as comprising a large heating cylinder 12 and two small cooling cylinders 13, 14.

The upper drying unit is herein represented as comprising a large heating cylinder 15 and two small cooling cylinders 16, 17.

These two drying units are located in line with each other and the printing units and are preferably located in substantially the same transverse vertical plane.

The web supply roll is denoted by 18 and is located at the opposite end of the press from the point of delivery.

The web is led through the press as follows:

The unprinted web passes from the supply roll 35 18 to and through the lower printing unit where the web is printed in multicolor on one side thereof. The web is then led to and around the heating cylinder 12 and cooling cylinders 13, 14 of the lower drying unit. From thence the web 40 is led to and through the upper printing unit where the web is printed in multicolor on the other side thereof. The web is then led to and around the heating cylinder 15 and cooling cylinders 16, 17 of the upper drying unit. The perfected web may then be directed from the upper 45 drying unit in the desired direction.

In Fig. 2, the lower printing unit is represented as a two color unit, the impression cylinder being denoted by 19 and its two form cylinders by 20, 21, which form cylinders are arranged around the side of the impression cylinder opposite a drying unit. The inking mechanisms for the form cylinders are denoted by 20a, 21a, which

inking mechanisms apply the ink to their respective form cylinders in the usual manner.

The upper printing unit for perfecting the web is herein represented as a two color unit, 5 the impression cylinder being denoted by 22 and its two form cylinders by 23, 24, which form cylinders are arranged around the side of the impression cylinder opposite a drying unit. The inking mechanisms for the form cylinders are 10 denoted by 23a, 24a, which inking mechanisms apply the ink to their respective form cylinders in the usual manner.

These two printing units are located in line 15 with each other at the required distance apart and they are also preferably located in substantially the same transverse vertical plane.

An oil offset mechanism 25 of a well known or approved form may be used for the purpose of keeping the packing clean on the upper impression cylinder 22 and eliminating not only smut that might be caused when the web is not absolutely dry, but will also remove from the packing any dried particles of ink that may be picked off by the make-ready when receiving the impression 25 from the upper printing unit.

The lower drying unit is herein represented as comprising a large heating cylinder 26 and two small cooling cylinders 27, 28.

The upper drying unit is herein represented as 30 comprising a large heating cylinder 29 and two small cooling cylinders 30, 31.

These two drying units are located in line with each other and the printing units and are located in substantially the same transverse vertical 35 plane.

The web supply roll is denoted by 32 and is located at the opposite end of the press from the delivery point.

The web is led through the press as follows:

40 The unprinted web passes from the web supply roll 32 to and through the lower printing unit where the web is printed in multicolor on one side thereof. The web is then led to and around the heating cylinder 26 and cooling cylinders 27, 28 of the lower printing unit. From thence the web is led to and through the upper printing unit where the web is printed in multicolor on the other side thereof. The web is then led to and around the heating cylinder 29 and cooling cylinders 30, 31 of the upper drying unit. The perfected web may then be directed from the upper drying unit in the desired direction.

The means for driving the several units is not shown or described herein, but any well known or approved means may be employed. It is understood that the lower and upper units may be driven separately either for the purpose of "making ready" or for permitting a single or two separate non-perfected multicolor products to be produced.

65 It is to be understood that guide rolls are provided for passing the web in prescribed paths from the web supply rolls 18 and 32 to the delivery points.

65 It will also be understood that any suitable heating medium, such as steam, may be supplied to the heating cylinders 12, 15, 26, and 29 and that any suitable cooling medium, such as water, may be supplied to the cooling cylinders 13, 14, 16, 17, 70 21, 22, 28, 30 and 31.

70 It will also be understood that any well known or approved quick drying inks may be used in the printing units.

75 From the above description it will be seen that I have provided arrangements of the several units

of the press whereby the inks on the freshly printed sides of the web may be thoroughly dried with a minimum travel of the web, the form cylinders of the several printing units at the same time being so positioned that ready access thereto may be obtained.

It is evident that various changes may be made in the form, construction and arrangements of the several parts without departing from the spirit and scope of my invention, and hence I do not intend to limit myself to the embodiments herein shown and described.

What I claim is:

1. In a web perfecting rotary press, lower and upper multicolor printing units, lower and upper drying units, each printing unit comprising an impression cylinder and a plurality of form cylinders arranged around the side of the impression cylinder opposite a drying unit, said printing units being located in substantially the same transverse vertical plane, a web supply roll, and means for leading the web through said units.

2. In a web perfecting rotary press, lower and upper multicolor printing units, lower and upper drying units, each printing unit comprising an impression cylinder and a plurality of form cylinders arranged around the side of the impression cylinder opposite a drying unit, said drying units being located in substantially the same transverse vertical plane, a web supply roll, and means for leading the web through said units.

3. In a web perfecting rotary press, lower and upper multicolor printing units, lower and upper drying units, each printing unit comprising an impression cylinder and a plurality of form cylinders arranged around the side of the impression cylinder opposite a drying unit, said printing units being located in substantially the same transverse vertical plane, a web supply roll, and means for leading the web through said units.

4. In a web perfecting rotary press, lower and upper multicolor printing units, lower and upper drying units, each printing unit comprising an impression cylinder and a plurality of form cylinders arranged around the side of the impression cylinder opposite a drying unit, each drying unit comprising a heating cylinder and one or more cooling cylinders, said printing units being located in substantially the same transverse vertical plane and said drying units being located in the same transverse vertical plane, a web supply roll and means for leading the web through said units.

5. In a web perfecting rotary press, lower and upper multicolor printing units, lower and upper drying units, each printing unit comprising an impression cylinder and a plurality of form cylinders arranged around the side of the impression cylinder opposite a drying unit, each drying unit comprising a heating cylinder and one or more cooling cylinders, said printing units being located in substantially the same transverse vertical plane, said drying units being located in substantially the same transverse vertical plane, said units being all located in line with one another, a web supply roll, and means for leading the web through said units.

6. In a web perfecting rotary press, lower and upper multicolor printing units, lower and upper drying units, each printing unit comprising an impression cylinder and a plurality of form cylinders arranged around the side of the impression cylinder opposite a drying unit, each

drying unit comprising a heating cylinder and one or more cooling cylinders, said printing units being located in substantially the same transverse vertical plane, said drying units being located in substantially the same transverse vertical plane, said lower and upper printing units

being located in substantially the same horizontal planes with their lower and upper drying units respectively, a web supply roll, and means for leading the web through said units.

5

HOWARD M. BARBER.
